UNITED STATES PATENT OFFICE.

JACK F. DAHL, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 30, 1922. Serial No. 610,030.

To all whom it may concern:

Be it known that I, JACK F. DAHL, a citizen of the United States of America, residing at East Orange, in the county of 5 Essex and State of New Jersey, have invented certain new and useful Improvements in Telephone-Exchange Systems, of which the following is a full, clear, concise, and exact description.

10 This invention relates to telephone exchange systems and more particularly to systems in which connecting operators are employed for extending connections in accordance with line designations displayed 15 before the operators by indicating mechanism.

In systems where certain offices are equipped with machine switching apparatus, whereas other offices employ manual operators for establishing connections, it is found 20 desirable that the manual operators be given information required for them to extend or complete connections incoming from the machine switching office without the necessity 25 of communicating orally with the calling subscriber or with other operators. To this end, each operator's position in the manual office is provided with a call indicator mechanism including a set of number indicating lamps which is operated automatically under the control of a sending 30 mechanism in the machine switching office. If connections are to be extended to party lines, the indicator mechanism, in addition to indicating to the operator the particular party on the indicated line to be called, either partially or wholly selects the proper 35 character of ringing current for calling the indicated party.

40 During the transition period when an exchange area is being changed from a manual operating basis to a machine switching or semi-automatic basis, and prior to the time when a particular manual office is required 45 to extend connections incoming from other offices operating upon a machine switching basis, it is necessary that the call extending circuits or trunks of the manual office be arranged to operate on a call wire basis. 50 When operating on a call wire basis, calls incoming to the manual office will originate in other manual offices and the originating operators will obtain trunk assignments in the usual manner over call wire circuits and 55 will orally inform the operator in the ter-

minating manual office of the designation of the desired line. When, then, the time arrives for cutting the originating office over to operate upon a machine switching basis, the circuits at the terminating manual office 60 must be modified to function therewith upon a call indicator basis.

To accomplish this with a minimum of delay, the trunk circuits of the manual office are equipped, when installed, with apparatus for enabling them to operate either upon a call wire basis or upon a call indicator basis and such apparatus, as for example, the indicating mechanism is strapped out until such time as the circuits are required 70 to operate upon a call indicator basis. At that time, the call indicator mechanism and the associated circuits are strapped into service and such apparatus of the trunk circuits as is used only when such circuits are 75 operating as call wire circuits is strapped out of service.

In some exchange areas, parties upon 80 party lines are selected semi-selectively, that is, a single source of ringing current is employed and connected to either the tip or the ring side of the called line, depending upon whether the bell of the desired party 85 is connected to the tip or to the ring side of the line, and since on four party lines, the bells of two of the parties are connected between the tip side of the line and ground, and the bells of the other two parties are connected between the ring side 90 of the line and ground, selection between the two parties whose bells are connected to the same side of the line is further made by manual application of the ringing current according to a ringing code. If the 95 exchange is equipped with standard indicator mechanism, which is designed to automatically control ringing selection, then it becomes necessary, since ringing selection is upon a semi-selective basis, to give some indication to the operator as to what code 100 she is to use to call the desired party. Provision must also be made for controlling the semi-selection of ringing current and the afore-said indication to the operator by 105 manually controlled means until such time as the operators' trunk circuits are cut-over from call wire to call indicator operation.

It is, therefore, the object of this invention to provide means for indicating to the operator, the required ringing selection to 110

be made to call a desired party on a party line.

More specifically, it is an object of this invention to provide means for selectively preparing circuits for the application of ringing current to either side of a party line and to indicate to the operator the manner in which the ringing current is to be then applied for calling one of four parties of a party line.

These objects are accomplished by providing a pair of ringing selection relays which may be variously operated by a group of master ringing keys during the period that the trunk circuits are operated upon a call wire basis or automatically by call indicator mechanism, when the trunk circuits have been cut over to operate upon a call indicator basis, to selectively prepare circuits for associating a ringing current source with either the tip or the ring side of a called line and to light a lamp steadily or intermittently for indicating which party of the two whose bells are connected to the same side of the line is to be called in response to ringing codes manually determined by the operator.

Other features of the invention not specifically referred to above will clearly appear from the following description and claims.

Figs. 1 and 2 of the drawings when arranged with Fig. 2 at the right of Fig. 1 diagrammatically represent such portions of a telephone exchange system are necessary to embody the present invention. Fig. 1 shows a calling subscriber's line A terminating in a machine switching office X of an exchange system and having access through a line switch, district selector and office selector to a trunk circuit at a terminating operator's position of a manual office. In addition, Fig. 1 shows in the lower portion thereof, such portions of a call indicator mechanism as are necessary to an understanding of this invention. Fig. 2 shows a trunk circuit at a terminating operator's position of a manual office which is arranged for initial operation on a call wire basis and for ultimate operation on a call indicator basis, together with a party line terminating in such office.

In the system herein disclosed, the apparatus at the originating machine switching office X, comprising the line switch 100, district selector 150, office selector 175, and sender 105 has been indicated very briefly as it enters only incidentally into the disclosure of this invention. For a full disclosure of apparatus of this character, reference may be had to the patent to F. A. Stearn and F. J. Scudder, No. 1,395,977, issued November 1, 1921, or to the patent to F. A. Stearn No. 1,505,171. The cord circuit at the operator's position O of Fig. 1 is of the usual manual type and indicates

one of the cord circuits of the office X in use prior to its cut-over from manual operation to machine switching operation.

The trunk circuit and indicating mechanism of Figs. 1 and 2 are of substantially the same type as disclosed in the patent to A. E. Lundell and E. H. Clark, No. 1,464,084, being modified, however, to selectively control the selection of ringing current in substantially the manner disclosed in the patent to A. E. Lundell, No. 1,312,791, issued August 12, 1919. In addition, and in accordance with this invention, the trunk circuit of Fig. 2 is further modified to permit an indication to the operator of the manner in which she must apply ringing current to the called line to call the party desired.

Inasmuch as the trunk circuit of Fig. 2 has been disclosed as provided with apparatus for initially operating it upon a call wire basis and for ultimately operating it upon a call indicator basis, straps 111, 112, 205 to 215 inclusive shown in full lines and straps 200 to 204, 247 and 248 shown in dotted lines have been provided for converting the trunk circuit. With the straps shown in full lines inserted, and the straps shown in dotted lines removed, the trunk circuit functions on a manual call wire basis in conjunction with originating manual operators' positions such as position O of office X. To convert the trunk circuit for operation upon a call indicator basis, after the exchange office X has been cut-over for machine switching operation, the straps shown in full lines are removed and the straps shown in dotted lines are inserted. In practice, the several connection terminals indicated by circles in connection with the several straps would be closely associated with each other on the switchboard frames and connection between them for example, would be accomplished at the time of the cut-over by a multi-terminal plug or the equivalent thereof.

The called line shown at the right of Fig. 2 has been disclosed with but one of the four substations shown in full, the bell circuits only of the remaining three substations C, D and E being disclosed. It is to be understood, however, that each of the substations is similar to the substation B with the exception of the manner in which the bell circuits are connected. It will be noted that stations B and D are disclosed with their bells connected between the tip side 243 of the line and ground and that stations C and E are disclosed with their bells connected between the ring side 244 of the line and ground.

Having now briefly described the apparatus employed in carrying out the objects of this invention and the general manner in which it functions, the invention will now be described more in detail. First, a de-

scription will be given of the apparatus as it functions when operating upon a call wire basis with the straps shown in full lines inserted and the straps in dotted lines removed. The invention will then be described as it functions after the trunk circuit has been changed over to operate upon a call indicator basis.

Connection extended on a call wire basis.—

- 10 It will be assumed that a subscriber in the office X desires a connection with the sub-
station B on a line terminating in the office Y, the designation of which line is 3578-W
and that this connection is to be established
15 wholly by manual means. The subscriber in
the office X will in the usual manner initiate
the call and obtain a connection with the op-
erator at position O who, upon ascertaining
20 that the calling subscriber desires a connec-
tion with a subscriber whose line terminates
in the office Y, will obtain the assignment of
a trunk circuit extending between offices X
25 and Y from the operator at position O' of the
office Y. This assignment is obtained over a
call wire circuit (not shown) extending be-
tween the offices. Having obtained the as-
signment, the operator at position O will then
30 forward designation of the desired line to
the operator in O' over the call wire circuit.
35 The operator at position O' having as-
signed a trunk circuit to the use of the op-
erator at position O, which trunk circuit will
be assumed to be the one disclosed terminat-
ing in the jack 142 at position O, will de-
40 press the assignment key 217 of this trunk
circuit. With the key 217 depressed, a cir-
cuit is established for the relay 220 which
may be traced from ground, strap 210, con-
45 tact of key 217, strap 212, the normal con-
tacts associated with the outer left armature
of relay 218, the inner right armature and
back contact of relay 219, the winding of
50 relay 220 to battery at the outer right arm-
ature and contact of relay 221. Relay 220
energizes in this circuit closing a locking cir-
cuit for itself from ground through the con-
55 tact of key 217, thence, as traced through
the winding of relay 220 to battery through
the inner right armature and front contact
of relay 220. Relay 220 also closes a circuit
60 for the assignment lamp 222 which may be
traced from ground through the outer right
armature and front contact of relay 220, lamp
222, to battery through the outer left
65 armature and front contact of relay 220. If
plug 231 is not at this time inserted in jack
232 an additional battery supply for lamp
222 is obtained at the intermediate armature
and back contact of sleeve relay 224. As-
70 suming, however, that the plug 231 is down,
a circuit is now established for relay 223
which may be traced from battery through
the strap 213, the lower armature and back
75 contact of sleeve relay 224, right winding
of relay 223, inner left armature and front

contact of relay 220, contact of key 217,
strap 210 to ground. Relay 223 now ener-
gizes closing a locking circuit for itself from
ground through its inner left armature and
front contact, through both of its windings, 70
lower armature and back contact of relay
224, strap 213 to battery.

With relay 223 energized, a circuit is now
established for relay 221 which may be
traced from battery through the winding of 75
relay 221 to ground at the right armature
and front contact of relay 223. Relay 221
upon energizing, opens the initial energiz-
ing circuit of relay 220 at its outer right
80 armature and contact and at its outer left
armature and front contact connects the in-
terrupter 226 to the back contact of the outer
right armature of relay 220 preparatory to
flashing the lamp 222 as hereinafter de-
85 scribed. Relay 221 also establishes a circuit
for relay 218 which may be traced from
ground through the winding of relay 218,
the inner right armature and front contact
of relay 221 to battery through the inner 90
right armature and front contact of relay
220. Relay 218 upon energizing, closes a
locking circuit for itself extending through
its winding, its outer right armature and
front contact to battery through the wind-
95 ing of relay 219. Relay 219, however, does
not operate in this locking circuit since its
winding is shunted by battery connected
through the inner right armature and con-
tact of relay 220.

With relays 218 and 223 energized, a cir-
cuit is now established for relay 225 which
may be traced from ground, strap 215, the
outer left armature and contact of relay 223,
winding of relay 225 to battery through the
inner left armature and contact of relay 218. 100
As soon as relay 218 operates, the holding
circuit for relay 220 is opened at the
break contacts associated with the outer left
armature of relay 218 and relay 220 there-
upon deenergizes, opening the shunt around
105 the winding of relay 219 to permit the
operation of the latter relay. With relay
220 deenergized, a circuit is now effective
for flashing the assignment lamp 222, which
circuit may be traced from ground through
110 the interrupter 226, the outer left armature
and front contact of relay 221, the outer
right armature and back contact of relay
220, lamp 222 to battery through the inter-
mediate armature and back contact of sleeve 115
relay 224. The operator noting the flashing
of lamp 222 is apprised of the fact that relay
225 is operated and that the master ringing
keys 250 are now associated with the trunk
circuit which she has assigned. 120

The operator now depresses a master ring-
ing key of the group 250 corresponding to
the party upon the party line with whom
the connection is desired. In the case as-
sumed, she depresses the key 252 correspond- 130

ing to the party W. With key 252 depressed, a circuit is established for relay 229 which may be traced from battery through the winding of this relay, the innermost 5 upper armature and contact of relay 225, strap 207, conductor 227, the upper spring of key 252, and its alternate contact to ground. A circuit is also established for relay 230 which may be traced from battery 10 through the winding of this relay, the lowermost armature and contact of relay 225, strap 208, conductor 228, lower spring and contact of key 252, to ground. Relays 229 and 230 upon energizing lock over their left 15 armatures and front contacts thereof to ground at the outer left armature and front contact of relay 219. The operation of relay 229 determines the side of the line to which current from the source 241 is to be applied and relay 230 determines the manner 20 in which this current is to be applied by the operator.

The operation of relay 225 disconnects the 25 tip and ring conductors 255 and 256 of the trunk circuit from the windings of relay 238 so that should the operator at position O insert the plug 141 of her cord circuit in the jack 142, of the trunk circuit, relay 238 will not operate, and consequently the relay 30 240 will not operate to shunt down relay 218 and to open the circuit of relay 225 before the operator at position O' has had time to operate a master ringing key.

The operator at position O' having depressed the master ringing key 252, now 35 tests the jack of the desired line to ascertain if it is busy or idle and if found to be idle extends connection to such line by inserting the plug 231 in the jack 232. With the plug 40 231 inserted in the jack 232, a circuit is established for the sleeve relay 224 extending from battery through the winding of this relay to ground through the sleeve of plug 231 and the sleeve of jack 232. Relay 45 224 upon operating disconnects the tip of the plug from the test conductor 235 leading to the operator's telephone set and connects the tip of the plug with the tip strand of the trunk circuit. At its lowermost armature, relay 224 opens the locking circuit of 50 relay 228, which in turn opens the circuits of relays 221 and 225. With relay 221 de-energized, the interrupter 226 is disconnected from the circuit through lamp 222 and lamp 222 is thereupon extinguished.

A circuit is now effective for the ringing lamp 236 which may be traced from battery through the intermediate armature and front contact of relay 224, left armature 55 and back contact of relay 237, lamp 236, the right armature and front contact of relay 230 to ground through the interrupter 226. The lamp 236 now flashes indicating to the operator that she should apply ringing current through the operation of key 60

234 in accordance with a code for ringing either the party W or the party M. Relay 225 upon releasing disconnects conductors 227 and 228 extending from the master ringing keys 250 through the windings of 70 relay 229 and 230 and connects the tip and ring conductors 255 and 256 of the trunk circuit extending from the jack 142 through the left windings of repeating coil 251 to the windings of relay 238. If, at this time, the operator at position O has connected with the trunk circuit, relay 238 operates over a circuit which may be traced from battery, ring of plug 141, ring of jack 142, strap 112, conductor 256, innermost lower 80 armature and back contact of relay 225, lower left winding of repeating coil 251, right armature and back contact of relay 253, strap 206, low resistance right winding of relay 238, high resistance left winding 85 of relay 238, strap 205, left armature and back contact of relay 253, upper left winding of repeating coil 251, upper armature and back contact of relay 225, conductor 255, strap 111, tip of jack 142, tip of plug 90 141 to ground at the cord circuit at position O. Relay 238, upon operating, closes an obvious circuit for relay 240 which in turn closes a shunt around the winding of relay 218. This shunt may be traced from ground through the winding of relay 218, the outer right armature and front contact of relay 218, the inner left armature and front contact of relay 219, the armature and contact of relay 240, strap 209 to ground at 100 the right armature and back contact of relay 223. Relay 218 now deenergizes, relay 219 being maintained over the circuit just traced to ground at the back contact and right armature of relay 223 under the control of 105 line relay 238.

Upon the operation of key 234, a circuit is established for ringing relay 233 which may be traced from battery through the intermediate armature and front contact of 110 sleeve relay 224, the outer right armature and contact of relay 219, winding of relay 233, contacts of key 234, normal contacts associated with the outer right armature of relay 218, the inner left armature and front contact of relay 219, the armature and contact of relay 240, strap 209, to ground at the right armature and back contact of relay 223.

Upon each energization of ringing relay 115 233 in response to the operation of key 234, it being assumed that to call party W at substation B, a ringing code of two long impulses is employed, with relay 229 energized as assumed, ringing current from the 120 source 241 is connected over the outer left armature and front contact of relay 229, the upper armature and front contact of relay 233, the upper armature and front contact of sleeve relay 224, tip of plug 231, tip 125 130

of jack 232, line conductor 243, to ground through the bell 242 at substation B. At the same time, the ring conductor 244 of the called line is connected to ground over the 5 ring of jack 232, ring of plug 231, lower armature and front contact of ringing relay 233 and the right armature and front contact of relay 229.

The subscriber B in response to two long 10 rings, removes his receiver from its switchhook, thereupon closing a circuit for the supervisory relay 239 as soon as the ringing key 234 is released. The circuit for relay 239 may be traced from battery, lower right 15 winding of repeating coil 251, relay 239, lower armature and back contact of relay 233, ring of plug 231, ring of jack 232, conductor 244, thence through the substation B returning over conductor 243, tip of jack 20 232, tip of plug 231, upper armature and front contact of relay 224, upper armature and back contact of relay 233 to ground through the upper right winding of repeating coil 251. Relay 239, upon energizing, 25 closes an obvious circuit for relay 249 which in turn, closes an obvious circuit for relay 253 and a circuit for relay 237. The circuit of relay 237 extends from ground through the intermediate armature and contact of relay 249, the break contacts of the 30 right armature of relay 237, winding of this relay, intermediate armature and front contact of relay 224 to battery. Relay 237 upon operating locks directly to ground 35 through the make contact of its right armature, and at its left armature and contact opens the circuit of ringing lamp 236, which is thereupon extinguished.

Relay 253 upon energizing, with relay 40 249 energized, reverses the connection of the windings of relay 238 with the circuit extending back to the cord circuit at position O, and relay 249 closes a shunt around the left high resistance winding of relay 238. 45 Relay 238 is now maintained energized over a circuit which may be traced from ground through the upper right winding of the repeating coil at position O, tip of plug 141, tip of jack 142, conductor 255, upper armature and back contact of relay 225, upper left winding of repeating coil 251, right armature and front contact of relay 253, strap 206, right low resistance winding of 50 relay 238, outer right armature and front contact of relay 249, strap 205, left armature and front contact of relay 253, lower left winding of repeating coil 251, innermost lower armature and back contact of relay 225, conductor 256, ring of jack 142, 55 ring of plug 141 to battery at the cord circuit at position O. With the high resistance winding of relay 238 shunted, the supervisory relay at the cord circuit of position O operates to indicate to the operator that 60 the called subscriber has responded.

Upon the termination of the conversation, between the subscriber in the office X and the subscriber B in the office Y, the operator at position O will receive the usual disconnect signal, the calling supervisory 70 signal being operated by the removal of the shunt about the high resistance winding of relay 238 at the armature and contact of relay 249, upon the deenergization of this relay, incident to the deenergization of relay 239 when the subscriber B restores his receiver to its switchhook. In response to the disconnect signals, the operator at position O removes the plug 141 from the jack 142 thereby opening the circuit extending 80 through line relay 238 at the office Y, causing the release of this relay and the consequent release of relay 240.

Upon the deenergization of relay 240, the holding circuit of relay 219 is opened 85 whereupon a circuit is established for the disconnect lamp 245 which may be traced from battery through the intermediate armature and front contact of relay 224, disconnect lamp 245 to ground at the outer 90 left armature and back contact of relay 219. The operator at position O' in response to the lighting of this lamp removes the plug 231 from the jack 232 thereupon opening the circuit of sleeve relay 224, thereby opening the circuit of lamp 245 and causing it to become extinguished. Since upon the deenergization of relay 219, the locking circuits of relays 229 and 230 were opened, and upon the deenergization of relay 224, the 100 holding circuit of relay 237 is opened, all apparatus employed in the establishment of the connection is now in its normal position.

Conversion of trunk circuit for operation upon relay call indicator basis.—When it becomes necessary to convert the trunk circuit shown in Fig. 2 for operation upon a call indicator basis, following the cut-over of the office X from a manual basis to a machine switching basis, straps 111, 112, 205 110 to 215, inclusive are removed and the straps 200 to 204 inclusive, 257, 258, 247 and 248 are inserted. Connections from subscribers' lines terminating in the office X are thereafter established with subscribers' lines 115 terminating in the office Y upon a semi-mechanical basis.

The subscriber A whose line terminates in the office X, desiring a connection with a party on a subscriber's line terminating in the office Y, will remove his receiver from its switchhook, and through the operation of the line switch 100 will obtain a connection with the central office sender 105 over the lower contacts of cams 101 and 102, and 120 will in response to the usual dial tone, dial the designation of the subscriber's line desired. It will be assumed in this case, that the calling subscriber desires connection with the line and party whose designation 125 130

is 3578 W. Having set the registers of the office sender 105 to register the designation of the desired line, the sender 105 proceeds to set the brushes of district selector 150 and the brushes of office selector 175 upon the terminals of an idle trunk circuit extending to the office Y, in the manner fully set forth in the aforesaid Patent No. 1,395,977, in accordance with the office designation of the office in which the desired line terminates.

As soon as the office selector 175 selects an idle trunk extending to the office Y, which will be assumed to be the trunk disclosed, a circuit is established for line relay 254 of the trunk circuit which may be traced from battery, left winding of relay 254, strap 257, left armature and back contact of relay 253, the upper left winding of repeating coil 251, the upper armature and back contact of relay 225, upper brushes of switches 175 and 150, lower contact of cam 103, through the controlling circuits of sender 105, over the lower contact of cam 104, lower brushes of switches 150 and 175, innermost lower armature and back contact of relay 225, lower left winding of repeating coil 251, right armature and back contact of relay 253, strap 258, to ground through the right winding of relay 254. Relay 254 responds to current flowing in this circuit and establishes a circuit for relay 220 which may be traced from battery through the outer right armature and contact of relay 221, the winding of relay 220, inner right armature and back contact of relay 219 to ground at the armature and contact of relay 254. Relay 220 upon energizing, locks through its inner right armature and contact to battery, at its outer right armature and front contact establishes the previously traced circuit for assignment lamp 222 and at its inner left armature and front contact prepares a circuit for the relay 223.

In response to the lighting of assignment lamp 222, the operator depresses key 217 whereupon a circuit is established from battery through the winding of relay 113, conductor 114, strap 204, the lower armature and contact of relay 224, right winding of relay 223, inner left armature and contact of relay 220, contact of key 217, strap 202, conductor 246, armature and back contact of relay 115 to ground at the right armature and back contact of relay 116. Relays 113 and 223 energize in this circuit, relay 223 locking from ground through its inner left armature and front contact through both of its windings and thence to battery through the winding of relay 113 as previously traced, as soon as key 217 is released. Relay 223 upon energizing, closes an obvious circuit for relay 221 which in turn, operates relay 218 over the circuit previously described. Relay 218 upon energizing, closes a locking circuit for itself

extending from ground through its winding, front contact of its outer right armature, to battery through the winding of relay 219, relay 219, however, not energizing at this time since its winding is shunted by battery connected through the inner right armature and contact of relay 220.

With relay 218 energized, a circuit is now established for relay 225 which may be traced from ground through the left armature and back contact of relay 116, the winding of relay 115, conductor 124, the outer left armature and front contact of relay 223, the winding of relay 225 to battery at the inner left armature and front contact of relay 218. With relay 225 energized, the tip and ring conductors 255 and 256 of the trunk circuit extending back to bank terminals of office selector 175 are disconnected from the windings of relay 254 and connected over straps 247 and 248 with conductors 117 and 118 extending to the indicator mechanism of Fig. 1. As soon as the windings of relay 254 are disconnected from the conductors of the trunk circuit, relay 254 deenergizes opening the locking circuit of relay 220, which in turn deenergizes removing the shunt from around the winding of relay 219. Relay 219 now energizes in the locking circuit of relay 218. With relay 220 deenergized and relay 221 energized, a circuit is established for flashing lamp 222 as previously traced for giving the operator a signal that impulses are being received from the distant sender 105 for recording the designation of the desired line upon the indicator mechanism which she has connected to the trunk circuit.

At the time relay 225 operated to open the circuit extending through the windings of relay 254 back to the office X, the sender 105 advances in the well known manner to a position in which it commences the transmission of code impulses for recording the designation of the desired line upon the indicator mechanism of Fig. 1. In accordance with well known practice, each code of impulses comprises a maximum of four impulses, the first and third impulses being either light positive or omitted entirely and the second and fourth impulses being either light or strong negative current.

At the indicator mechanism of Fig. 1, upon the energization of relay 113 in series with relay 223, ground potential is connected to conductor 123 through the armature and contact of relay 113 and the armature and back contact of relay 122 for furnishing locking ground for the various relays of the indicator mechanism and for furnishing operating ground to the armatures of control relays 119, 120 and 121. The circuit established by the operation of relay 225 over conductors 117 and 118 may now be traced in part from the sender 105

through the lower contact of cam 103, upper brushes of switches 150 and 175, upper armature and front contact of relay 225, strap 248, conductor 118, winding of marginal control relay 119, windings of negatively polarized relay 120, windings of positively polarized relay 121, conductor 117, strap 247, innermost lower armature and front contact of relay 225, conductor 256, thence over the lower brushes of switches 175 and 150 and the lower contact of cam 104 to the sender 105.

For registering the party designation W, the sender 105 transmits a code of two impulses comprising a strong negative impulse followed by a weak negative impulse. In response to the first impulse of strong negative current, the negatively polarized relay 120 and the marginal relay 119 operate. Relay 120 upon operating closes a circuit which may be traced from ground on conductor 123 through the armature and contact of relay 120, conductor 125, left armature and back contact of relay 126, left winding of relay 127 to battery through the left winding of relay 126. Relay 127 energizes but relay 126 does not receive sufficient current to cause its energization. Upon the energization of relay 127, a locking circuit is established therefor, extending from battery through the left winding of relay 126, left winding of relay 127, right winding of relay 126, inner right armature and contact of relay 127, to ground on conductor 123. Since at this time, the right winding of relay 126 is shunted by ground connected through the armature and contact of relay 120, relay 126 does not energize. With relay 127 energized, a circuit is established for switching relay 128 which may be traced from battery through the winding of relay 128, right armature and back contact of switching relay 129, outer right armature and front contact of relay 127 to ground on conductor 123. Relay 128 now locks through its winding, the winding of relay 129, the right armature and contact of relay 128 to ground on conductor 123. Relay 129, however, does not energize in this locking circuit since its winding is shunted by ground connected through the outer right armature and contact of relay 127.

Relay 119 upon energizing establishes a circuit from ground on conductor 123 through the armature and contact of relay 119, conductor 130, the outer right armature and back contact of relay 126, the outer left armature and back contact of relay 129, upper winding of stations register relay 108 to battery. Relay 108, upon energizing, locks from battery through both of its windings and its innermost lower armature and contact to ground on conductor 123. When the first impulse of the stations code ter-

minates, relays 119 and 120 deenergize, relay 120 removing the shunt from around the right winding of relay 126 permitting this relay to energize in the locking circuit of relay 127. Relay 126 at its inner right armature and contact now closes a further shunt around the winding of switching relay 129.

In response to the second impulse of weak negative current, negatively polarized relay 120 energizes, closing a circuit extending from ground on conductor 123 through the armature and contact of relay 120, conductor 125, the left armature and front contact of relay 126, to battery through the left winding of relay 126. Relay 126 is maintained energized over this circuit but relay 127 is shunted and deenergizes. When the impulse ceases, relay 120 deenergizes, unlocking relay 126. Since both relays 126 and 127 are now deenergized, the shunts previously mentioned extending about the winding of relay 129 are opened, and relay 129 energizes in the locking circuit of relay 128.

The remaining codes of impulses are now received in the usual manner in accordance with the thousands, hundreds, tens and units digits of the desired line designation, a pair of switching relays such as 131, 132 and 133, 134, operating in response to each code of impulses transmitted until upon the completion of the transmission of the units code, switching relays 135 and 136 become operated and locked. This operation is in accordance with the disclosure of Patent No. 1,464,084 hereinbefore referred to. When relay 136 operates, an obvious circuit is closed for relay 116, which opens the circuit previously traced through the windings of relays 115 and 225 causing their release. A circuit is also closed for lighting the lamps of the indicator for displaying the complete line designation. The circuit for the W stations lamp 137 may be traced from battery through the right armature and contact of switching relay 136, lamp 137, the innermost upper armature and back contact of stations register relay 109, to ground through the lowermost armature and contact of stations register relay 108.

The conductors 138 and 139 are connected to ground at contacts of the stations register relays for operating the ringing current selection relays 229 and 230 of the trunk circuit in the following manner: The circuit for relay 230 may be traced from battery through the winding of relay 230, lowermost armature and front contact of relay 225, strap 201, conductor 139, the lower armature and back contact of relay 110, the innermost upper armature and front contact of relay 108, the upper armatures and back contacts of relays 107 and 106 to the ground at the left armature and front contact of switching relay 133. The circuit

for relay 229 may be traced from battery through the winding of this relay, the innermost upper armature and contact of relay 225, strap 200, conductor 138, the upper armature and back contact of relay 110 to ground at the lower armature and front contact of relay 108. It will be noted that relays 229 and 230 are energized and locked over their inner left armatures and front contacts to ground at the make contacts of the outer left armature of relay 219, during the transmission of the hundreds code of impulses and therefore, ringing current selection is accomplished before relay 225 de-energizes following the operation of units switching relay 136.

Upon the deenergization of relay 225, the control conductors 117 and 118 extending from the indicator mechanism of Fig. 1 to the sender 105 are disconnected, the sender is thereupon released from connection with the established connection and a talking circuit is established over the upper contacts of cams 101 to 104 inclusive, in the well known manner. As soon as this talking circuit is established, line relay 254 again energizes, closing a circuit from ground at its armature and front contact through the inner right armature and front contact of relay 219 through the winding of relay 219 to battery for maintaining this relay energized and for shunting down relay 218. Relay 218 thereupon deenergizes.

The operator, noting the display of the line designation inserts plug 231 into jack 232 whereupon relay 224 energizes, opening the circuit of lamp 222 and the holding circuit of relays 113 and 223. Relay 113 now deenergizes removing ground from the holding conductor 123 thereby releasing all apparatus of the indicator. A circuit is now closed for the ringing lamp 236 which may be traced from ground through the interrupter 226, the right armature and front contact of relay 230, lamp 236, left armature and back contact of relay 237 to battery through the intermediate armature and front contact of relay 224. The lamp 236 is thereupon flashed to indicate to the operator that she should throw the ringing key 234 in accordance with the code necessary to ring either the party W or the party M on the line whose designation is displayed by the indicator. When the operator throws the key 234, the circuit for applying ringing current is established as hereinbefore described. When the called subscriber responds to the ringing current, relays 239, 249 and 253 operate as hereinbefore described and relay 237 energizes to open the circuit of lamp 236. Relay 253, upon operating, reverses the battery and ground connections from the windings of relay 254 to the conductors of the trunk circuit for supervisory purposes. Upon the termina-

tion of the conversation, when subscriber A restores his receiver to its switch-hook, relay 254 deenergizes, opening the locking circuit of relay 219. Relay 219, thereupon closes the previously traced circuit for disconnect lamp 245. From this point, the restoration of the trunk circuit proceeds in the manner previously described. Restoration of the apparatus in office X is accomplished in the usual manner. The trunk circuit has been described hereinbefore in connection with the establishment of a call to a party W of a party line. If it is desired to signal the party R, either the party R key of the master keys 250 or the stations register relays 108 and 109 of the indicator will be operated and ringing selection relay 229 will be energized, relay 230 not being operated. When, therefore, the circuit for ringing lamp 236 is established, the lamp will glow steadily since the armature of relay 230 is connected at its back contact directly to ground rather than through the interrupter 226. The operator will then operate the ringing key 234 to apply ringing current to the called line in a manner to apply ringing current distinctively to bells of substations B and D. It may, for example, be assumed that the subscriber at substation D will respond when his bell rings with a single long ring.

To signal the party J, the J key of the master ringing keys 250 or the stations register relay 107 is operated whereupon neither relays 229 nor 230 are operated and consequently current from the source 241 is applied to the ring conductor 244 of the called line and the ringing lamp 236 is lighted steadily to indicate that the ringing key 234 should be operated to ring the bells of substations C and E with a single long ring. To ring the party M, the M key of the master keys 250 or the stations register relay 106 is operated whereupon relay 230 is operated, relay 229 being unoperated. With only relay 230 operated, ringing current from source 241 is applied to the ring conductor 244 of the called line and the ringing lamp is flashed to indicate that the ringing key 234 should be operated to ring the bells of substations C and E with two long rings.

What is claimed is:

1. In a telephone exchange system, an incoming line, an outgoing line, a plurality of substations connected to said outgoing line, a signal associated with each of said substations, means for interconnecting said lines, a source of signaling current, means controlled over said incoming line for selectively associating said source of current with said outgoing line, a signaling device for indicating the manner in which said source of current should be applied to said outgoing line, and manually operated means

for applying said current in accordance with said indication.

2. In a telephone exchange system, an incoming line, an outgoing line, a plurality of 5 substations connected to said outgoing line, a signal associated with each of said substations, the signals of certain of said substations being responsive to signaling current applied to one side of said line and the 10 signals of the remaining substations being responsive to signaling current applied to the other side of said line, means for interconnecting said lines, a source of signaling current, means controlled over said incoming line for associating said source with either side of said outgoing line, a signaling device for indicating the manner in which 15 current from said source should be applied to said outgoing line, and manual means 20 for applying said current in accordance with said indications.

3. In a telephone exchange system, an incoming line, an outgoing line, a plurality of substations connected to said outgoing 25 line, a signal associated with each of said substations, the signals of certain of said substations being responsive to signaling current applied to one side of said line and the signals of the remaining substations 30 being responsive to signaling current applied to the other side of said line, means for interconnecting said lines, a source of signaling current, means controlled over said incoming line for associating said 35 source of current with either side of said outgoing line, a key for distinctively applying said source of current, and a signaling device for indicating the distinctive manner in which said current should be applied.

4. In a telephone exchange system, an incoming line, an outgoing line, a plurality of substations connected to said outgoing lines, a signal associated with each of said substations, the signals of certain of said 45 substations being responsive to signaling current applied to one side of said line and the signals of the remaining substations being responsive to signaling current applied to the other side of said line, means 50 for interconnecting said lines, a source of signaling current, substation selecting means, means controlled thereby for associating said source of current with either side of said line, a key for distinctively applying said source of current, and a signaling device controlled by said substation 55 selecting means for indicating the distinctive manner in which current from said source should be applied.

5. In a telephone exchange system, an incoming line, an outgoing line, a plurality of substations connected to said outgoing line, a signal associated with each of said substations, means for interconnecting said 60 lines, a source of signaling current, sub-

station selecting means, manually operable means for applying current from said source to said outgoing line for operating said signals in a distinctive manner, and means controlled by said substation selecting means 70 for indicating the distinctive manner in which said signaling current should be applied.

6. In a telephone exchange system, an incoming line, an outgoing line, a plurality of 75 substations connected to said outgoing line, a signal associated with each of said substations, means for interconnecting said lines, a source of signaling current, substation selecting means, means for applying 80 current from said source to said outgoing line for operating said signals in a distinctive manner, a lamp signal, and means under the control of said substation selecting means for lighting said lamp signal in a 85 distinctive manner for indicating the distinctive manner in which said signaling current should be applied.

7. In a telephone exchange system, an incoming line, an outgoing line, a plurality of 90 substations connected to said outgoing line, a signal associated with each of said substations, the signals of certain of said substations being responsive to signaling current applied to one side of said line and the signals of the remaining substations being 95 responsive to current applied to the other side of said line, means for interconnecting said lines, a source of signaling current, substation selecting means, a signaling device, a key for applying current from said source to said outgoing line, and a pair of relays controlled selectively by said selecting means, one of said relays determining to which side of said line said source of current shall be applied and the other of said relays operating said signaling device to indicate the distinctive manner in which current from said source shall be applied.

8. In a telephone exchange system, an operator's position, a trunk circuit incoming thereto, an indicating device at said position, means operated over said trunk circuit for setting the indicating device in accordance with the designations of desired lines, 110 an outgoing line, a plurality of substations on said outgoing line, a signal associated with each of said substations, means at said position for interconnecting said trunk circuit and said line, a source of signaling current, manually operable means for applying current from said source to said outgoing line for operating said signals in a distinctive manner, and means controlled by said indicating device in accordance with the stations setting thereof for indicating to the operator the distinctive manner in which said signaling current should be applied.

9. In a telephone exchange system, an operator's position, a trunk circuit incoming 115

thereto, an indicating device at said operator's position, means operated over said trunk circuit for setting the indicating device in accordance with the designations of 5 desired lines, an outgoing line, a plurality of substations on said outgoing line, a signal associated with each of said substations, the signals of certain of said substations being responsive to signal current applied to one 10 side of said line, and the signals of the remaining substations being responsive to signaling current applied to the other side of said line, means at said position for interconnecting said trunk circuit and said line, 15 a source of signaling current, a signaling device, manual means for applying current from said source to said line, and a pair of relays controlled selectively by said indicating device in accordance with the stations 20 setting thereof, one of said relays determining to which side of the line said source shall be applied and the other of said relays operating said signaling device to indicate the distinctive manner in which current 25 from said source shall be applied by said manual means.

10. In a telephone exchange system, an incoming line, an outgoing line, a plurality of substations connected to said outgoing 30 line, a signal associated with each of said substations, means for interconnecting said

lines, a source of signaling current, station 35 selecting keys for normal association with said interconnecting means, an indicating device, means for transmitting impulses over said incoming line for setting said indicating device to register the line designation of a desired subscriber, means for applying current from said source to said outgoing line for operating said signals in a distinctive manner, means for cutting said station 40 selecting keys out of service and for cutting said indicating device into service, and means controlled either by said keys or by said indicating device for indicating the 45 distinctive manner in which signaling current should be applied.

11. In a telephone exchange system, an incoming line, an outgoing line, a plurality of substations connected to said outgoing 50 line, a signal associated with each of said substations, means for interconnecting said lines, a source of signaling current, means controlled over said incoming line for selectively associating said source of current with 55 said outgoing line, and manually operated means for applying said current in accordance with specified ringing codes.

In witness whereof, I hereunto subscribe my name this 29th day of December A. D., 60 1922.

JACK F. DAHL.
